CLAIM

The ornamental design for a portion of a display screen with graphical user interface, as shown and described.

DESCRIPTION

FIG. 1 is a perspective view of one embodiment of a portion of a display screen with graphical user interface; and,

FIG. 2 is a perspective view of another embodiment of a portion of a display screen with graphical user interface.

The broken lines shown in the drawings represent a display screen and environmental data, none of which forms any part of the claimed design.

1 Claim, 2 Drawing Sheets Fig. 1
